ABSTRACT

A high signal-to-noise ratio (S/N) is obtainable in an apparatus for transforming luminous intensity into a voltage which is in exact inverse proportion to the luminous intensity. The apparatus is constituted by connecting a first controlling means t_1 for current controlling in series to a photoconductive element R_p having non-linear characteristic of $R_p = K \cdot E^{-\gamma}$, where R_p is resistance, E is luminous intensity and K and γ are constants, and by connecting a second controlling means t_2 so as to receive a voltage V_p across both ends of the photoconductive element R_p and to give a signal, which is approximately proportional to $V_p^{1-\gamma}$, of said first controlling means t_1 , which controls the current I_p of the photoconductive element R_p to be approximately proportional to the value $E^{\gamma-1}$, and as a result causes the voltage V_p to be approximately in inverse proportion to the luminous intensity E .

FIG 7

ILLUMINATION-TO-VOLTAGE CONVERSION APPARATUS

BACKGROUND OF THE INVENTION

This invention relates to an apparatus for transforming luminous intensity to voltage wherein the voltage is in exact inverse proportion to the luminous intensity.

In general, the resistance of a photoconductive element is not in exact inverse proportion to the luminous intensity, but has the following relationship:

$$Rp = K \cdot E^{-\gamma} \quad (1)$$

wherein Rp is the resistance of the photoconductive element, E is the luminous intensity and K and γ are constants. Therefore, if a current I_p , which is constant irrespective of the voltage V_p across the ends of the element, is applied, then by Ohm's law, the following relationship is obtainable, wherein the voltage V_p is in inverse proportion to the γ th power of the luminous intensity:

$$V_p = K \cdot E^{-\gamma} \cdot I_p \quad (2)$$

Hitherto, among actual apparatus requiring that an output be in exact inverse proportion to the luminous intensity, an apparatus constituted as shown in FIG. 1, wherein logarithm-transforming means such as, a logarithm-compressor circuit and a logarithm-expander circuit, is employed.

In the conventional apparatus of FIG. 1, a photoconductive element Rp is connected to a constant current source CIS so that a constant current flows through the photoconductive element Rp . The voltage V_p across the element Rp is

$$V_p = Rp \cdot I_p = K \cdot E^{-\gamma} \cdot I_p \quad (2.1)$$

and is given to a logarithmic-compressor circuit LCC to produce the following output:

$$\log V_p = -\gamma \log E + \log K \cdot I_p \quad (2.2)$$

Then the abovementioned output is applied to a multiplier circuit MC, so as to be multiplied by $1/\gamma$ to produce the following output:

$$(1/\gamma) \log V_p = -\log E + (1/\gamma) \log K \cdot I_p \quad (2.3)$$

namely,

$$\log V_p(1/\gamma) = \log (K \cdot I_p)(1/\gamma) \cdot E^{-1} \quad (2.4)$$

The abovementioned output is then applied to an inverse logarithmic transforming circuit, i.e., a logarithmic-expander circuit LEC to produce the following output:

$$V' = (K \cdot I_p)(1/\gamma) \cdot E^{-1} \quad (2.5)$$

wherein

$$V' = V_p(1/\gamma) \quad (2.6)$$

Thus, the output V' of the logarithmic-expander circuit LEC is in exact inverse proportion to the luminous intensity E .

The abovementioned prior art apparatus has the shortcoming of having a low signal-to-noise (S/N) ratio, since noises mixed at points a or b in FIG. 1, which points are in a prior stage to the stage for the logarithmic-expansion by the circuit LEC, are expanded to a great extent by the expansion, resulting in poor signal-to-noise ratio in the output voltage V' . Hitherto, a circuit of very complicated configuration was necessary to eliminate such expansion of the noise.

SUMMARY OF THE INVENTION

This invention purports to provide an apparatus capable of attaining good S/N ratio in transforming luminous intensity to voltage with good linearity characteristic, by employing rather simple circuit constitution.

BRIEF EXPLANATION OF THE DRAWING

FIG. 1 is a schematic block diagram showing the above-mentioned conventional apparatus for transforming luminous intensity to voltage;

FIG. 2 is a schematic block diagram showing the fundamental construction of the apparatus of the present invention;

FIG. 3 is a graph showing the relationship between the input voltage and the output voltage of the second controlling means of FIG. 2;

FIG. 4 is a schematic circuit diagram showing the fundamental circuit configuration of an apparatus embodying the present invention;

FIG. 5 is a schematic circuit diagram showing one actual example of the apparatus embodying the present invention;

FIG. 6 is a schematic circuit diagram showing a circuit equivalent to the circuit of FIG. 5; and

FIG. 7 is a graph showing the relationship between the relative input luminous intensity and the relative output current flowing through the photoconductive element.

DETAILED DESCRIPTION OF THE INVENTION

The apparatus of the present invention has a fundamental configuration as shown in FIG. 2, wherein a photoconductive element Rp and a first controlling means $t1$, which controls the current of the element Rp , are connected in series across a D.C. power source DCS, and both ends of the photoconductor element Rp are connected to input terminals of a second controlling means $t2$ which applies a controlling signal to the first controlling means $t1$.

The first controlling means $t1$ controls the current I_p of the element Rp in proportion to its control input voltage Y received from the output of the second controlling means $t2$. The second controlling means $t2$ receives as an input voltage the voltage V_p across both ends of the element Rp . The output terminals "Out" are connected to respective ends of the photoconductive element Rp .

As has been explained with reference to the equations (1) and (2), the output voltage V_p is given as: $V_p = K \cdot E^{-\gamma} \cdot I_p$. Accordingly, if the current I_p is controlled to be

$$I_p = C \cdot E^{-\gamma-1} \quad (3)$$

then, from the equations (2) and (3), the following relationship is obtainable:

$$V_p = K \cdot E^{-\gamma} \cdot C \cdot E^{-\gamma-1} = K \cdot C \cdot E^{-1} \quad (3.1)$$

Thus, if the relationship of the equation (3) is obtainable by means of the characteristic of the second controlling means t_2 , then the exact inverse proportion between the luminous intensity and the output voltage V_p is obtainable.

In order to attain the abovementioned characteristic, the second controlling means t_2 should have the following characteristic between its input X and output Y :

$$Y = hX^{1-\gamma} \quad (3.2)$$

where h is a constant. With the characteristic as above-mentioned, the output Y of the second controlling means for an input voltage of $V_p = KC \cdot E^{-1}$ becomes as follows:

$$Y = hX^{1-\gamma} = h(KC \cdot E^{-1})^{1-\gamma} = K_3 \cdot E^{-\gamma-1} \quad (3.3)$$

where K_3 is a constant. Accordingly, the first controlling means t_1 controls its output current I_p so as to be proportional to the output $K_3 \cdot E^{-\gamma-1}$ of the second controlling means, and therefore, the voltage V_p across both ends of the photoconductive element R_p , namely, the voltage at the output terminal OUT of this apparatus corresponds to the equation (3.1).

The characteristic of the equation (3.2) is the theoretical characteristic, which is shown by a solid curve in the graph of FIG. 3. However, it has been difficult to attain such a characteristic by means of a simple circuit. However, in practical operation, the abovementioned characteristic can be approximated by the following characteristic if constants are properly selected:

$$Y = b + d \cdot \log(X + \gamma) \quad (3.4)$$

The dotted curve in FIG. 3 shows the curve of the function of the equation (3.4).

The abovementioned characteristic of the equation (3.4) can be realized by utilizing a logarithmic function of a diode or diodes.

A preferred fundamental example embodying the present invention is shown in FIG. 4, wherein details of the first and the second controlling means t_1 and t_2 are shown. In FIG. 4, the first controlling means comprises a first transistor T_1 , the collector of which is connected to one end of the photoconductive element R_p . The second controlling means t_2 comprises a second transistor T_2 , the base and the emitter of which are connected across both ends of the photoconductive ele-

ment R_p , and to the collector of which are connected a diode D and a variable resistor R_2 in series. The junction point p between the collector of the second transistor T_2 and the diode D is for logarithmic-conversion and is connected to the base of the first transistor T_1 .

In general, the voltage across both terminals of a diode or diodes in series connection is proportional to the logarithm of the current flowing through the diode, and accordingly, the voltage V_{pq} between the points p and q is given as

$$V_{pq} = R_2 \cdot i + d \cdot \log i \quad (3.3)$$

wherein d is a constant, and i is the current flowing through the diode D and the resistor R_2 .

Since the collector current I_p is proportional to the base input voltage V_{pq} of the transistor T_1 ,

$$I_p = L \cdot V_{pq} = L \{R_2 \cdot i + d \cdot \log i\} \quad (4)$$

wherein L is a constant. The constants L and d should be properly selected by suitably selecting circuit constants, in order to attain good approximation between the theoretical $Y = X^{1-\gamma}$ curve and the present $Y = b + d \cdot \log(X + \gamma)$ curve. Thus, the relationship of the equation (3.1) is approximated.

FIG. 5 shows a more practical embodiment provided with two variable resistors R_2 and R_v as characteristic-approximation adjusting means. The apparatus also provides a pair of thermistors H_1 and H_2 for temperature compensation, a current adjusting transistor Q_3 and a shunt resistor R_s . A Darlington connection consisting of a pair of transistors Q_1 and Q_2 is employed in place of the second transistor T_2 , in order that only very little input current to the base of the transistor Q_1 is required. The transistor Q_3 is provided connecting its collector, emitter and base to the positive end of the D.C. source, one end of the photoconductive element R_p , and a moving arm of the variable resistor R_v , respectively. As will be explained later, the variable resistor R_v is for adjusting the curve for good approximation in the high luminous intensity range, and the variable resistor R_2 is for adjusting the curve for good approximation in the low luminous intensity range. Further, a series connection of several diodes may be employed in place of the diode D to ensure higher reverse breakdown voltage. In considering the operation, the circuit of FIG. 5 can be represented by the equivalent circuit of FIG. 6.

In FIG. 6 since both ends of the variable resistor R_v are connected across both ends of the D.C. source DCS , a divided voltage is applied to the movable contact of the variable resistor R_v and this voltage applied to the base of the transistor Q_3 . On account of the shunt resistor R_s , most of the emitter current of the transistor Q_3 flows through the shunt resistor R_s , and accordingly, very little of the emitter current flows through the photoconductive element R_p . Accordingly, the emitter current of the transistor Q_3 is little influenced by the change of the current I_p flowing through the photoconductive element R_p , ensuring a constant voltage V_o between the collector and the emitter of the transistor Q_3 . This voltage V_o is dependent only on the

position of the moving contact of the variable resistor R_v .

The total of the abovementioned voltage V_o and the voltage V_p across the ends of the photoconductive element R_p is applied across the emitter and the base of the transistor T_2 , as illustrated in FIG. 6.

Now, defining the center value of the luminous intensity as E_o , the resistance and the current of the photoconductive element for this luminous intensity to be R_{po} and I_{po} , respectively, and the collector current of the transistor T_2 and the voltage between points p and q for the abovementioned condition to be i_o and V_{pqo} , respectively, then the following relationships are given from the equations (1), (3) and (3.3):

$$R_{po} = K \cdot E_o^{-\gamma}$$

accordingly

$$K = R_{po}/E_o^{-\gamma}$$

$$I_{po} = C \cdot E_o^{-\gamma-1}$$

accordingly

$$C = I_{po}/E_o^{-\gamma-1}$$

By substituting the abovementioned K and C of the equations (4.1) and (4.2) into the equations (1) and (3), the following relationships are given:

$$R_p = K \cdot E^{-\gamma} = (R_{po}/E_o^{-\gamma}) E^{-\gamma}$$

$$I_p = C \cdot E^{-\gamma-1} = (I_{po}/E_o^{-\gamma-1}) E^{-\gamma-1}$$

Next, by defining i' as the collector current of the transistor T_2 for the condition $V_p = 0$, on account of the linear characteristic between the base voltage $V_o + V_p$ and collector current i of the transistor T_2 , the following relationship is given:

$$i = i' + K_1 \cdot V_p, \text{ (where } K_1 \text{ is a constant)}$$

(5.3)

Also, from the equations (3.1) and (5.3),

$$i = i' + K_1 \cdot K \cdot C \cdot E^{-1} = i' + K_2 \cdot E^{-1}$$

(5.4)

wherein $K_2 = K_1 \cdot K \cdot C$. And accordingly,

$$(i - i')E = k_2$$

(5.4)

and by applying the aforementioned condition of i_o for E_o in the equation (5.4),

$$(i_o - i')E_o = K_2$$

(5.5)

From the equations (5.4) and (5.5),

$$i = i' + (i_o - i') (E_o/E)$$

(6)

5 From the equations (4) and (6),

$$I_p = L \{ R_2 \cdot (i' + (i_o - i') [E_o/E]) + d \cdot \log(i' + (i_o - i') [E_o/E]) \} \quad (8)$$

10 For a small luminous intensity, the logarithmic term of the equation (8) is negligibly small, and accordingly, the condition $i' \ll (i_o - i) (E_o/E)$ is realized for a practical circuit condition. Therefore, we can express I_p as follows:

$$I_p \approx L \cdot R_2 \cdot E_o \cdot (i_o - i') \cdot E^{-1}$$

(9)

20 Since this equation (9) has the value R_2 but excludes the value R_v , the adjustment for the proximation of the curve $Y = b + d \log(X + \gamma)$ to the theoretical curve $Y = X^{1-\gamma}$ can be made by adjusting only the variable resistor R_2 .

25 For a large luminous intensity, the logarithmic term becomes predominant and therefore, we can express I_p , as follows:

$$I_p = + L \cdot d \cdot \log(i' + E_o \cdot (i_o - i') E^{-1}) \quad (10)$$

Since this equation (10) does not have R_2 , the adjustment for the approximation can be made by adjusting only the variable resistor R_v . Namely, by adjusting the resistor R_v , the voltage V_o between the collector and the emitter of the transistor Q_3 is varied, and the current i' in the equation (6) is also varied.

Thus, for both the ranges of large luminous intensity and small luminous intensity, the characteristic curve of the apparatus of FIG. 5 is well approximated to that of the theoretical curve.

From the equation (3) for the value I_{po} and E_o ,

$$I_{po} = C \cdot E_o^{-\gamma-1}$$

(10.1)

and from the equations (3) and (10.1),

$$I_p/I_{po} = (E/E_o)^{-\gamma-1}$$

(10.2)

From the equation (3.1),

$$V_{po} = K \cdot C \cdot E_o^{-\gamma}$$

(10.3)

and from the equations (3.1) and (10.3),

$$V_p/V_{po} = (E/E_o)^{-1}$$

(10.4)

In FIG. 7 the ordinate represents values of I_p/I_{po} , and the abscissa represents values of E/E_o . The solid curve indicates the theoretical characteristic which is represented by the equations (3) and (3.1) wherein $\gamma = 0.85$, while the dotted curve indicates the experimental result of the circuit of FIG. 5. In the dotted curve, the curve

in the left and right parts are adjusted by the variable resistors R_2 and R_v , respectively. Thus, by adjusting the variable resistors R_2 and R_v , the dotted line can be well approximated to the solid line.

The apparatus of the present invention has a low noise level for the following reason:

Possible noises produced in a circuit such as illustrated in FIG. 6 takes place at the bases of the transistors. Accordingly, we should consider the noises at the bases. A small part of the noise at the base of the transistor Q_3 is applied to the base of the transistor T_2 , since most of the emitter current of the transistor Q_3 flows in the shunt resistor R_s . The noise at the base of the transistor T_2 produces the noise in the current i . From the equations (2) and (4) the following relationship is found:

$$V_p \propto R_2 \cdot i + d \log i,$$

Namely, the output voltage V_p consists of a first part which is proportional to the current i and a second part which is a logarithmic compression of the current i . A noise, i.e., a small fluctuation in the current i , makes a resultant noise, i.e., a small fluctuation in the voltage V_p . Such a resultant noise consists of a first part originated from the first part $R_2 \cdot i$, i.e., a proportional part, and of a second part $d \log i$, i.e., a logarithmic compressed part; and therefore, the resultant noise is no greater than the conventional logarithmic expanded noise as explained with reference to FIG. 1.

What is claimed is:

1. Illumination-to-voltage conversion apparatus comprising:

a direct current source,

a photoconductive element having a resistance proportional to the $-n$ th power of the received luminous intensity,

first controlling means connected in series with said photoconductive element across said direct current source for controlling the current flowing through said photoconductive element,

second controlling means connected to receive as an input signal the voltage appearing across both ends

of said photoconductive element and producing an output signal for controlling said first controlling means to regulate the current through said photoconductive element to be approximately proportional to the $1 - \gamma$ th power of said voltage appearing across said photoconductive element, and a means for taking out as an output signal the voltage across both ends of the photoconductive element.

10 2. The apparatus of claim 1 wherein said second controlling means has a characteristic to produce an output signal represented by $b + d \cdot \log(X + r)$ for an input signal X , wherein b , d and r are constants.

15 3. The apparatus of claim 1 wherein said first controlling means comprises a first transistor having a collector electrode which is connected to said photoconductive element, said second controlling means comprising at least one second transistor having a collector electrode which is connected in series to at least one diode for logarithmic transformation and a variable resistor, the base and emitter electrodes of said first transistor being connected across the series combination of said diode and said variable resistor, and the base and emitter electrodes of said second transistor being connected across said photoconductive element.

20 4. The apparatus of claim 3, further including a third transistor connected in series with said photoconductive element, the base and emitter electrodes of said second transistor being connected across the series combination of said photoconductive element and said third transistor, the base electrode of said third transistor being connected to a source of reference voltage.

25 5. The apparatus of claim 4 wherein said second controlling means comprises two second transistors connected in series in a Darlington configuration and connected in series with at least two diodes.

30 6. The apparatus of claim 5 wherein said source of reference voltage comprises a potentiometer connected across said direct current source.
